GEORGE ABEL AND JOHN PEDDER, OF TEMPERANCEVILLE, PENNSYLVANIA.

Letters Patent No. 94,170, dated August 31, 1869.

IMPROVEMENT IN INGOT-MOULDS.

The Schedule referred to in these Letters Patent and making part of the same.

To all whom it may concern:

Be it known that we, **GEORGE ABEL** and **JOHN PEDDER**, of Temperanceville, in the county of Allegheny, and State of Pennsylvania, have invented a new and useful Improvement in Ingot-Moulds; and we do hereby declare the following to be a full, clear, and exact description thereof, reference being had to the accompanying drawing, making part of this specification, in which—

Figure 1 is a perspective view of our ingot-mould; Figure 2, by a longitudinal sectional view of one side, illustrates one feature of our invention; and

Figure 3 is a cross-section of our improved mould as enclosed in a box or flask, and illustrative of its manner of use.

Like letters of reference indicate like parts of each. The nature of our invention consists in making an ingot-mould for casting metallic ingots, with a surface exteriorly ribbed or corrugated, the ribs or corrugations running lengthways of the mould; also in strengthening the sides by a rib deepest or heaviest midway between its ends, and tapering either way; also in making such a mould with a tongued and grooved joint along the "part" or division of the mould.

To enable those skilled in the art to make and use our invention, we will proceed to describe the same, and its manner of use.

The ingot-mould is cast in two halves, *a a¹*, and the halves are united together by a tongue-and-groove joint, as at *b*. The inner faces of such moulds usually have heretofore been planed in order to secure a smooth surface on which to cast the ingot; and planing metals, it is well known, is both costly and slow. This objection we overcome by casting the inside face of each half of the mould, as well as of the tongue and groove, on a chill, thereby securing in both the desired smooth face.

As soon as the half moulds *a a¹* are cast, we place them together as shown in fig. 1, under a considerable pressure, the object of which is to prevent other than a uniform shrinkage in both. The tongue of the one enters the groove in the other, and by their wedge-like action, when under pressure, the two halves are drawn to the same shape, and held there while cool-

ing. We thus secure uniform shrinkage in both, and in connection with the ribbing hereinafter described, prevent the warping of either.

The face of the mould which forms the outside of the moulds *a a¹* is so shaped as to give a corrugated exterior to each half, *a a¹*, as at *c c*, and also so as to give in each half one or more heavy ribs *e*, which are largest midway between the ends, and taper therefrom either way, as more clearly shown in fig. 2. The object of the corrugations *c* and ribs *e*, is to secure the requisite strength in the mould, with less metal, or to make a more economical disposition of the metal used in the casting of the moulds, both with reference to its strength proper, and with reference to its power to resist the warping to which it is subject, both at the time the halves are cast and when in use for casting ingots.

Ingot-moulds have heretofore been usually held together when in use by bands and wedges. As an improvement on this mode, we propose to pack them in a strong flask, *a*, and interpose between the two a packing of sand or other like suitable cushioning-material. In this way, the resistance to the warping-tendency, instead of being confined to two or three bands at or near the opposite ends of the mould, is distributed evenly along from end to end, so that two halves of the mould are held securely in place while the casting is being done, and at the same time the danger of breakage is greatly lessened. Ingot-moulds thus made and used are far more durable, as well as less expensive and less difficult to handle, being lighter than those made and used in the manner heretofore adopted.

What we claim as our invention, and desire to secure by Letters Patent, is—

A two-part ingot-mould, having a tongued and grooved joint, and exterior corrugations *c c*, substantially as described.

In testimony whereof, we, the said **GEORGE ABEL** and **JOHN PEDDER**, have hereunto set our hands.

GEORGE ABEL.

JOHN PEDDER.
